UNITED STATES PATENT OFFICE.

KYLE E. STANT, OF CONNERSVILLE, INDIANA.

DESIGN FOR A RADIATOR CAP.

Application filed May 19, 1928. Serial No. 26,768. Term of patent 3½ years.

To all whom it may concern:

Be it known that I, KYLE E. STANT, a citizen of the United States, residing at Connersville, in the county of Fayette and State of Indiana, have invented a new, original, and ornamental Design for a Radiator Cap, of which the following is a specification, reference being had to the accompanying drawing, forming part thereof.

In the drawings Fig. 1 is a top plan view of the radiator cap. Fig. 2 is a side elevation thereof. Fig. 3 is a front elevation thereof.

I claim:

The ornamental design for a radiator cap, as shown.
